UNITED STATES PATENT OFFICE.

WILLIAM TEE HANCOCK AND MURAT BOYLE, OF KANSAS CITY, MISSOURI.

APPARATUS FOR REFINING OILS.

Application filed October 8, 1923. Serial No. 667,231.

To all whom it may concern:

Be it known that we, WILLIAM TEE HANCOCK and MURAT BOYLE, citizens of the United States, residing at Kansas City, in the county of Jackson and State of Missouri, have invented certain new and useful Improvements in Apparatus for Refining Oils; and we do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to an apparatus for refining heavy hydrocarbon oils to produce oils of lower specific gravities. In other words, the invention relates to an apparatus for converting heavy hydrocarbon oils into lighter hydrocarbon oils to produce a product commercially known as gasoline.

The invention differs essentially from other apparatuses known to us in that it comprehends the use of super-heated steam as the sole medium for raising the temperature of the oil.

We are aware that prior to our invention steam has been introduced into cracking systems at various steps in the cycle of operations but we are not aware that prior to our invention super-heated steam has been used to co-mingle with the heavy oils and, as the heating medium, provide the necessary temperature and pressure to cause the oil to crack.

The invention will be clearly understood by reference to the following description in connection with the accompanying drawing, in which—

The figure is a diagrammatic view of an apparatus for carrying out our invention, the still and the tower being shown in vertical, longitudinal section.

Referring now to the drawing by numerals of reference:

1 designates a boiler from which the steam will be delivered at a working pressure of about 1500 pounds (approximately 815 degrees F.). The steam passes from the boiler to the still 2 through a pipe 3, the pipe 3 communicating with the boiler 1 through a pipe 4 and discharging into the respective ends 5 and 6 of the still 2.

The still 2 is a shell and has longitudinally disposed tubes 8 therein supported at the

ends by the crown sheets 9 and 10, the crown sheets being spaced from the ends of the still so that the spaces 5 and 6 are large enough to provide steam spaces to feed the open ends of the tubes 8. The tubes are perforate, the perforations 11 admitting the steam into the oil chamber 12. The oil is fed into the oil chamber through a pipe 13 and we prefer to introduce the oil into the oil chamber in a preheated condition; that is, we prefer to raise its temperature to about 800 degrees F.

As the oil enters the oil chamber, the steam will pass from opposite ends of the still; that is, from the opposite chambers 5 and 6 into the pipes and co-mingle with the oil at very high pressure and temperature, causing the oil to separate into oils of different specific gravities. The vapors will pass through the central outlet 14 in the oil chamber through an elongated, vertical vapor chamber or separation chamber shown as a tower 15 where the heavier ends of the distillates will be condensed to gravitate back into the still, the lighter ends passing off through the outlet 16 into the condenser 17 through a pipe 18, the condensed vapors passing through the condenser 17 being the product sought.

The initial boiling point of the product will be about 130 F. and the end point approximately 430 F.

If the steam is introduced into the still at about 1500 pounds working pressure, the temperature of this superheated steam will be about 815 F. plus, or 1368 B. t. u. per pound of steam. If 85 gallons of feed water per hour is used, the boiler will generate 93,000 pounds of steam and, obviously 93,000 pounds of steam per hour at 1500 pounds working pressure will crack 1,060 gallons of commercial 30 gravity oil into 95% of the volume.

It will be apparent from the foregoing that the incoming oil will be subjected to the action of the highly super-heated steam at very high pressure and since it is well known that the higher the temperature and pressure of steam, the greater the efficiency, it will be apparent that the oil can be cracked in a highly efficient manner.

We have specifically set the pressure at 1500 pounds and the temperature at 815 degrees but we do not wish to be limited to these exact pressures and temperature because we comprehend that the method may

be carried out satisfactorily by introducing steam at from 1000 to 2000 pounds pressure and from 600 to 1000 degrees F.

The oil is supplied to the still at about 800 degrees F., then the steam pressure is turned on, the separation taking place in the vapor chamber or tower 15.

The higher pressures and temperatures may require special boilers but there are 10 now in existence boilers which are capable of generating steam up to 1500 pounds working pressure so we recommend this pressure as being within commercial possibilities.

Suitable valves may be provided where- 15 ever desired; for example, we have shown valves 19 and 20, the former for controlling the flow of steam and the latter for the condenser.

Attention is also called to the fact that 20 the steam issuing from the perforations 11 in the pipes 8 has the effect of providing separate stream lines of steam for the oil, the steam passing in all directions so as to penetrate the oil and quickly raise it to a crack- 25 ing temperature; the pressure, of course, being enough to cause the heavy oils to quickly be converted into lighter end vapors.

If the method is carried out in accordance with our invention there will be practically 30 no coke or carbon formed; therefore, the process may be carried on over long periods because there will be no shutdowns for the removal of coke. Since the use of dry heat is eliminated, there will be no danger of 35 burning the still; consequently, liability of

weakening of the still from this cause will be eliminated.

What we claim and desire to secure by Letters-Patent is:

1. In a system for converting heavy hydrocarbon oils into lighter hydrocarbon oils, the combination with a horizontal still having perforate pipes running longitudinally thereof, crown sheets supporting the ends of the pipes, the crown sheets being spaced 45 from the ends of the still to provide steam spaces at the respective ends thereof, steam inlets at the respective ends of the still, a separator chamber connected to the upper portion of the still, and a condenser connected to the top of the separating chamber.

2. In a system for converting heavy hydrocarbon oils into lighter hydro-carbon oils, a horizontal shell still, divided into a central oil space and two end steam spaces, 55 two sets of longitudinally disposed pipes in the oil space, each set communicating with one of the two end steam spaces, the portions of the pipes within the oil space having their walls perforated, a separation chamber connected to the upper portion of the still, a condenser connected to the separation chamber, and a high pressure boiler having means of communication with the steam spaces whereby steam may be admitted to the oil at 60 abnormal temperatures and pressures.

In testimony whereof we affix our signatures.

WILLIAM TEE HANCOCK.
MURAT BOYLE.
